UNITED STATES PATENT OFFICE

149,135

DESIGN FOR A GARDEN TOOL RACK

De Witt McCann, Irving Berlin, and Frank L. Graham, Los Angeles, Calif.

Application April 24, 1946, Serial No. 128,910

Term of patent 14 years

(Cl. D33—3)

To all whom it may concern:

Be it known that we, De Witt McCann, Irving Berlin, and Frank L. Graham, citizens of the United States, residing at Los Angeles, in the county of Los Angeles, State of California, have jointly invented a new, original, and ornamental Design for a Garden Tool Rack, of which the following is a specification, reference being had to the accompanying drawing, forming part thereof.

Fig. 1 is a plan view of a garden tool rack showing our new design; Fig. 2 is a front elevational view thereof and Fig. 3 is an end elevational view thereof.

We claim:

The ornamental design for a garden tool rack, as shown.

DE WITT McCANN.
IRVING BERLIN.
FRANK L. GRAHAM.
